UNITED STATES PATENT OFFICE.

JOHN PETER HILL, OF PULASKI, VIRGINIA.

COLLAPSIBLE TURN-TABLE.

1,161,673.

Specification of Letters Patent.

Patented Nov. 23, 1915.

Application filed April 19, 1915. Serial No. 22,428.

To all whom it may concern:

Be it known that I, JOHN P. HILL, a citizen of the United States, residing at Pulaski, in the county of Pulaski and State 5 of Virginia, have invented a new and useful Collapsible Turn-Table, of which the following is a specification.

The device forming the subject matter 10 of this application is a turntable adapted to be employed by section foremen and others for manipulating hand or motor cars.

The invention aims to provide a turntable 15 which may be folded into collapsed form and be carried readily upon a hand or motor car.

The invention aims to improve the frame or track portion of the turntable, and to provide novel means for supporting the turntable for swinging movement.

It is within the province of the disclosure 20 to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed, without departing from the spirit of the invention.

In the accompanying drawings:—Figure 35 1 shows the invention in top plan; Fig. 2 is a longitudinal section; Fig. 3 is a bottom plan of the turntable, the same being folded and collapsed; Fig. 4 is a top plan showing the turntable disposed transversely of the 40 track and in the position which it will assume when the car is trundled off of the turntable; Fig. 5 is a fragmental transverse section showing the means whereby the cross members or braces are pivotally assembled with the side portions of the frame; to the end that the frame may be folded up; Fig. 6 is a fragmental longitudinal section of the support on which the frame portion of the turntable is mounted to swing, 45 parts appearing in elevation. Fig. 7 is a top plan showing a modified form of the

invention; Fig. 8 is a vertical longitudinal section of the structure shown in Fig. 7; Fig. 9 is a transverse section of the structure shown in Fig. 7; Fig. 10 is a top plan showing the turntable of Fig. 7 in folded condition; Fig. 11 is a cross section taken approximately on the line 11—11 of Fig. 10. Fig. 12 is a side elevation of the structure shown in Fig. 6, parts being in section. 55 60

In the accompanying drawings, the numeral 1 indicates the rails of a track, the supporting ties appearing at 2.

In carrying out the present invention there is provided a turntable comprising a 65 collapsible frame embodying side members or tracks 3 each carrying at one end an abutment 100. The tracks 3 may be angle members and when this construction is resorted to, each track 3 comprises a base flange 4 70 and a side flange 5, the side flanges 5 of the respective tracks 3 being disposed adjacent to each other, so as to coöperate with the inner edges of the rails 1 in a manner to be pointed out hereinafter. Mounted upon 75 the outer faces of the side flanges 5 of the tracks 3 are sockets 6 adapted to receive rectangular fingers 7 formed at the ends of the cross members 8 which preferably are in the form of bars. 80

It will now be understood that the frame portion of the turntable may be extended so as to coöperate with the rails 1, as clearly shown in Fig. 1, or, if desired, and when the occasion for the use of the turntable is 85 passed, the frame of the turntable may be collapsed to the compact form shown in Fig. 3. A means is provided for holding the tracks 3 of the turntable frame in spaced relation to each other as shown in Fig. 1 of 90 the drawings, and with this end in view, a hook 9 is pivoted as shown at 10 to one of the side flanges 5 of the tracks 3.

The bill of the hook is denoted by the numeral 11 and is adapted to be received in 95 an opening 12 formed in one of the terminal cross members 8. The hook 9, therefore, contacts with the said cross member 8 and with the tracks 3, to hold the frame in the extended position shown in Fig. 1 and in such 100 condition that it may coact with the rails 1 of the railroad track proper.

Means is provided whereby the turntable frame may be swung from parallelism with the rails 1 to angular relation with respect thereto, and be tilted downwardly at one end, Figs. 1 and 4 being compared at this point. With the above end in view, there is provided a supporting member which is shown in clearest outline in Figs. 6 and 12, the supporting member comprising a hollow base 22 having an upstanding neck 14 receiving for rotation a standard 15 provided at its upper end with an eye 16. The standard 15 includes a reduced stem 17 extended downwardly through the base 22 and carrying superposed nuts 18 which coact with the base to hold the standard on the base against vertical displacement, without, however, interfering with the rotation of the standard 15. Mounted to rock in the eye 16 of the standard 15 is a loop-shaped brace 20 which is fixed to and depends from the central cross member 8.

In practical operation, the base 22 of the supporting member is placed on one of the ties 2 as shown in Fig. 1, the tracks 3 extending longitudinally of the rails 1. Owing to the fact that the brace 20 on the intermediate cross member 8 of the turntable frame is journaled for rocking movement in the eye 16, the turntable frame may be inclined with respect to the horizontal, as shown in Fig. 2. In this connection it is to be noted that, as indicated at 23, the side flanges 5 of the tracks 3 of the turntable frame engage with the inner edges of the rails 1 and thus the tracks of the turntable frame are aligned vertically with the rails. When the parts are positioned as above described, referring particularly to Fig. 2, the car which is to be manipulated is trundled onto the inclined turntable tracks 3 until the car lies above the supporting member and is balanced. Then the turntable frame is rotated until it stands approximately at right angles to the rails 1 as clearly shown in Fig. 4, whereupon one end of the frame may be depressed and the car may be trundled off the turntable, to one side of the rails 1. In order to return the car to the rails, the operation above described is reversed.

When the occasion for the use of the turntable has passed, the bill 11 of the hook 9 is withdrawn from the opening 12 in one of the cross members 8. The turntable thereupon loses its rigidity and the tracks 3 may be brought into close relation to each other as clearly shown in Fig. 3, the fingers 7 of the cross members 8 rotating in the sockets 6. The turntable now is in such a shape that it may be hung up readily on the car or be otherwise supported thereon, the structure taking up a minimum amount of room.

In that form of the invention which is disclosed in Figs. 7, 8, 9, 10 and 11, a pair of side members or tracks 50 are shown, the

same being provided, each, at one end with upstanding stops 62. The tracks 50 preferably are in the form of angle members, each track comprising a vertical flange 51 and a horizontal flange 52. Sockets 53 are attached to the inner faces of the vertical flanges 51 of the tracks, and in the sockets 53 are mounted pivotally, the upturned ends 54 of a single cross member 55 reinforced by a depending, loop-shaped brace 56 mounted to rotate in an eye 57 constituting a part of a standard which is journaled in a base 58, after the manner in Fig. 7. Bearings 59 are secured to the inner faces of the vertical flanges 51 of the tracks, and in the bearings are journaled the ends of loop-shaped brackets 60 having seats 61 which receive the cross member 55.

When the seats of the braces 60 are engaged with the cross member 55, the tracks 50 will be held in parallel relation. By lifting the braces 60, so that the seats 61 no longer engage with the cross member 55, the side members or tracks 50 may be swung together as shown in Fig. 10. When the parts are thus arranged, a resilient latch 63 on the horizontal flange of one track cooperates with the horizontal flange of the other track, as shown in Fig. 11, to hold the tracks in nested parallel relation. 95

Having thus described the invention, what is claimed is:—

1. In a turntable, a cross member; tracks pivoted to the ends of the cross member for movement toward and away from each other; and a supporting structure on which the cross member is mounted to rock vertically and to swing horizontally. 100
2. In a turntable, a cross member; tracks pivoted to the ends of the cross member for movement toward and away from each other; means for holding the tracks in parallel relation; and a support on which the cross member is mounted for vertical rocking movement and for horizontal swinging 110 movement. 105
3. In a turntable, a base; a standard journaled in the base and provided with an eye; a brace mounted to rock in the eye; a cross member to which the brace is attached; and tracks pivoted to the ends of the cross member for movement toward and away from each other. 115
4. In a turntable, a cross member; a pair of tracks pivoted to the ends of the cross member; braces extended transversely of the cross member and provided with seats receiving the cross member, the ends of the braces being pivoted to the tracks for swinging movement transversely of the plane defined by the tracks; and a supporting structure on which the brace is mounted for vertical rocking movement and for horizontal swinging movement. 120
5. A turntable comprising a collapsible 125

frame including tracks mounted to move endwise toward and away from each other; and a support on which the frame is mounted for rotation and for tilting movement 5 as an entity.

In testimony that I claim the foregoing

as my own, I have hereto affixed my signature in the presence of two witnesses.

JOHN PETER HILL.
